United States Patent Office

Des. 183,871
Patented Nov. 11, 1958

183,871

MILK BOTTLE CARRIER

Robert C. Adams and Irma O. Adams, Escondido, Calif.

Application December 13, 1956, Serial No. 44,187

Term of patent 14 years

(Cl. D58—5)

FIG. 1.

FIG. 2.

FIG. 3.

FIG. 4.

FIG. 5.

Fig. 1 is a perspective view of a milk bottle carrier, showing our new design;

Fig. 2 is a top plan view thereof;

Fig. 3 is a front elevational view thereof;

Fig. 4 is a bottom plan view thereof; and

Fig. 5 is an end elevational view thereof, taken from the right side of Fig. 1.

We claim:

The ornamental design for a milk bottle carrier, substantially as shown.
